United States Patent Office.

AUGUSTIN L. TAVEAU, OF CHAPTCO, MARYLAND.

Letters Patent No. 101,540, dated April 5, 1870.

REVOLVING SULKY-HARROW AND SEEDER, COMBINED.

The Schedule referred to in these Letters Patent and making part of the same.

I, AUGUSTIN L. TAVEAU, of Chaptico, in the county of St. Mary's and State of Maryland, have invented certain improvements in a machine more particularly described by me in the specification of a patent granted to me on the 4th day of May, 1869, No. 89,812, under the title of a Revolving Sulky-Harrow and Seeder, Combined. I will now only proceed to describe more recent improvements in the same machine, of which the following is a specification.

Description of the Drawings.

Figure sheet 1, is a side elevation of the harrow and seeder, combined.

Figure sheet 2, is a rear view of the same.

Sheet 3 is a plan of detail.

General Description.

The rims of the main wheels A are perforated with open spaces on each side of the cleats, to avoid clogging with dirt, and also to increase their traction. These cleats are strengthened by ribs around the inner or outer sides of the wheel-rims, as fancy elects, and the spokes are arched at their extremities when the wheel-rims are so perforated.

The segments R are bolted to the arms D, and are sustained by the rollers V overlapping their flanges.

The quadrants T are secured upon a bar, Z, which passes through the frame E under the flooring.

The lever P is secured on this bar Z to the right of the driver's seat, and has a stop on one side, for engaging with the notches in the radial bar O.

This radial bar O is bolted down on the middle and rear cross-pieces.

The lever P, operating through the bar Z and quadrants T, actuates the segments R and arms D, for raising, lowering, or gauging the revolving harrow.

The revolving harrow-cylinder M is formed by twisting a square bar of iron a quarter circle, and slipping on it the sockets h. These sockets may be separated by washers of any desirable thickness or material.

The sockets are tightened toward the center of the cylinder by a screw-nut at each end of the cylinder-bar inside of the arms D, and a loose washer plays between these screw-nuts and the arms D, for the purpose of avoiding too much friction.

Into these sockets & teeth g are secured at their base by bolts, and near the ends of the sockets by wooden pins r, similar to the original machine.

The ends of the square bar are turned off, to furnish the journals e, and at the end of each journal is a pin for engaging with the slip-clutches on the pinions C.

If desirable, the bar forming the cylinder M may be round, and the sockets h may be keyed upon it in any preferred pattern; and, in land free of stones and roots,

the socket and wooden-pin arrangement may be superseded by a plain tooth slipped on the bar like the sockets, and separated by washers, as aforesaid.

The hub of the main wheel A, as seen in the plan of detail, is slightly turned off, to receive the movable chain-wheel No. 2. This hub is also mounted with ribs, for engaging with the clutches on the chain-wheel No. 2; and the inner side of this chain-wheel has a collar, for receiving the fork of the rod a', which is hooked onto the foot-lever U, as seen in sheet 2.

This lever U is pivoted to the cross-piece S, and has a shoe, which engages with the trigger Q'. This trigger is also pivoted to the cross-piece S, and has a spring behind it, for pressing it into gear with the shoe of the lever U. A pin in front of the trigger prevents its passing the center.

The rod a' slides through a clamp bolted to the under side of the frame E near the cross-piece S.

A spring on this side of the frame E presses against the rod a', and thus holds the chain-wheel No. 2 in gear with the ribs on the main-wheel hub when the shoe of the lever U is released from the trigger Q'.

An endless chain, No. 5, on the chain-wheel No. 2 operates the chain-pinion No. 4.

This chain-pinion No. 4 has a cog-pinion on its inner side, which meshes with pinion No. 3.

This pinion No. 3 is movable, and may be held out of gear by withdrawing the inner key from its journal, and then slipping it back toward the box No. 1, and there confine it by putting the key in the hole outside of it.

The rods in the grain and guano-box No. 1 are mounted with flanges, for distributing the contents of the box through the holes in the bottom.

The slides in the box-bottom are set to a gauge by thumb-screws underneath the box.

The seeding-rods are secured in the box by suitable boxes bolted to the bottom.

The heels of the rods rest in pipes in the side of the box opposite the pinions, and the heads of the journals of the pinions have a slot, into which is fitted the ends of the seeding-rods, which are tenoned for the purpose, and are thus rendered removable at will. These journals rest in pipes in the side of the box next the pinions, and are entered from the inside.

A cam on the inner side of the chain-wheel No. 2 operates the grass-seed rod No. 8, which bears against a spring on the side of the frame E.

The rod No. 8 has a small roller on its forward end, for traversing the cam.

This rod is pivoted on the journal of the roller V, and its rear end is provided with an eye, for hooking onto the grass-seed traveler-rod.

This revolving harrow and seeder may be attached to a steam-plow, when desirable, by unshipping the

pole, and attaching it to the plows by suitable bars and bolts.

Claims.

What I claim as my invention, and desire to secure by Letters Patent, is—

1. The construction and arrangement of the ribs and open rims and traction-cleats and wheels A, constructed and operating as and for the purpose set forth.

2. The arrangement of the segments R, arms D, quadrants T, and rollers V, in combination with the rod Z, lever P, and radial bar O, operating as and for the purpose herein set forth.

3. The arrangement of the movable clutch and cam-wheel No. 2, chain No. 5, and chain-pinion No. 4, in combination with pinion No. 3, hub-ribs on wheel A,

foot-lever U, spring trigger Q², hook-rod a', and spring and grass-seeder rod and spring No. 8, operating as and for the purpose set forth.

4. The construction and arrangement of the cylindrical harrow M, sockets h, teeth g, braces r, and socket-rings w, constructed and operating as and for the purpose herein set forth and described.

5. The arrangement of the slip clutch pinions C and clutch-pins m, in combination with the journals e, all to a revolving harrow and seeder combined, operating substantially as and for the purpose herein set forth and described.

AUGUSTIN L. TAVEAU.
